UNITED STATES PATENT OFFICE

105,629

DESIGN FOR A WRENCH

Herman W. Zimmerman, North Chicago, Ill.,
assignor to Automotive Maintenance Ma-
chinery Co., North Chicago, Ill., a corporation
of Illinois

Application January 2, 1937, Serial No. 66,872

Term of patent 14 years

To all whom it may concern:

Be it known that I, Herman W. Zimmerman, a citizen of the United States, residing at North Chicago, county of Lake, State of Illinois, have invented a new, original, and ornamental Design for a Wrench, of which the following is a specification, reference being had to the accompanying drawing, forming a part thereof.

Figure 1 is a perspective view of a wrench showing my new design; and

Fig. 2 is a top plan view of the same, only a part of the handle being shown for convenience of illustration.

I claim:

The ornamental design for a wrench, as shown and described.

HERMAN W. ZIMMERMAN.
